[57] CLAIM

The ornamental design for a flat-plate nozzle for a vacuum cleaner, substantially as shown and described.

DESCRIPTION

FIG. 1 is a perspective view of a flat-plate nozzle for a vacuum cleaner, showing my new design;
FIG. 2 is a top plan view thereof;
FIG. 3 is a bottom plan view thereof;
FIG. 4 is a side elevational view thereof;
FIG. 5 is an enlarged fragmentary sectional view thereof, taken along line 5—5 of FIG. 3.
